ASH TRAY

Margaret H. Lyon, New York, N. Y.

Application August 10, 1939, Serial No. 289,360

2 Claims. (Cl. 206—72)

This invention relates to shallow receptacles adapted for use as ash trays, as coasters and for other purposes where it is desired to support an article out of contact with a supporting surface, such as a table or other piece of furniture.

It is an object of the invention to provide a receptacle of the type described which may be easily and cheaply manufactured and thrown away after having been used only once or a few times.

It is a further object of the invention to provide a receptacle suitable for the purposes intended which is reversible and usable in either of two positions with equal advantage, and which is adapted to carry advertising, pictorial or other ornamental printed matter or decoration on both sides of the bottom member.

It is a still further object of the invention to provide a receptacle or support of the type described which is made up of a separable bottom and side wall members which are respectively adapted to be interchanged with other members of similar form.

The use of ash trays, coasters and similar receptacles and supports as a means of carrying advertising for display in hotels, restaurants and other public places is well known, and there is a demand for articles of this type which are cheap enough to permit of their use for only a limited period and then discarded.

However, as heretofore available, ash trays bearing printed advertising matter have been too expensive to encourage wide distribution for advertising purposes, due in part to the expense of printing or stamping the advertising matter on the individual trays. Simple flat disc coasters have not presented such a problem because their form has made them susceptible of automatic feeding and manipulation in printing and other decorating operations. However, it has not been of advantage to print or decorate such coasters on both sides because it is impractical to reverse them once they have been used to support a beverage glass and have become wet or stained by the beverage.

According to my invention, the ash tray or other receptacle is made of separable parts, the bottom usually being made of a flat disc, printed and decorated on both sides, and the side walls being formed of an open-ended tubular member provided intermediate its ends with a recess or ledge adapted to support the bottom disc in either of the two possible positions. This construction insures that the bottom disc is spaced from the table or other supporting surface. This

is desirable as creating an air space, preventing overheating and damage to the finish of the supporting surface in case the receptacle is used as an ash tray. When it is to be used as a coaster 5 the spaced relation of the bottom to the supporting surface is an advantage in that it prevents marring or soiling of the appearance of the side of the disc that is beneath, thus preserving its appearance and usefulness for later use in the 10 top or exposed position. At the same time, when the bottom disc has been reversed, bringing the previously used and probably soiled surface beneath, this surface is kept out of contact with the table or other piece of furniture upon which 15 it is disposed. It will be seen that irrespective of the use to which the receptacle is to be put, it serves to present twice the area for advertising display that is afforded by the present trays and, moreover, permits a given receptacle to be 20 the medium for carrying two entirely different, or differing but related, forms of advertising.

The construction of the ash tray, coaster or other shallow receptacle in separable parts has, among others, the advantage that it permits interchangeability of the bottom discs or holders 25 with others made of different material or which are differently printed or decorated. Thus, it is within my invention to provide a holder,—the open-ended tubular member,—of a relatively permanent type and material and to associate therewith a disc of a relatively inexpensive material. For example, the holder may be made of metal, advantageously a light metal such as aluminum which may be spun or otherwise shaped to the 30 desired form from tubular or sheet material and suitably finished, as by lacquering. Many other materials of a more or less permanent nature will suggest themselves, such as various of the moldable plastics, impregnated fibrous materials, etc. From the standpoint of cost of materials and simplicity of manufacturing operations, 35 as well as usefulness and appearance, I find that the holder may be made very advantageously from various types of paper, asbestos and other sheet materials, usually but not necessarily impregnated, and I describe my construction with more particular reference to the use of various combinations of asbestos and paper.

When the receptacle is intended to serve as an 40 ash tray, the open-ended tubular holder and the bottom disc should be made, in their surface portions at least, of a fire resistant material. In the case of coasters, it is desirable that the bottom disc be somewhat water absorbent but, at 45 the same time, sufficiently impervious to water

and other liquids to insure that liquids spilled thereon will not pass through.

In making ash trays according to the invention, various forms of fire resistant sheet material may be used for the holder and the bottom disc, such as impregnated paper. I have found, however, that my construction makes it possible to use asbestos to better advantage than heretofore. It is recognized that it is difficult to print or decorate asbestos. By providing a separable bottom member in the form of a flat disc I have overcome the difficulty that has heretofore been met with of handling and manipulating asbestos ash trays to produce a printed or other decoration thereon. In the form of discs, asbestos lends itself readily to printing and decorating processes. I have also found that when asbestos is laminated with a more water resistant material to form the bottom disc, the resulting disc is particularly suitable for use in coasters, the asbestos providing the desired water absorbent qualities while the supporting water resistant material prevents the water from passing through.

Other objects and advantages of the invention will appear as the description proceeds.

In the drawing:

Fig. 1 is a perspective view of one form of the invention with the bottom and side walls in assembled relation and usable as an ash tray, a coaster, or for other purposes;

Fig. 2 is a part perspective, part section view of the bottom disc;

Fig. 3 shows a part side elevation and part section on the line 3—3 of Fig. 1;

Fig. 4 is a vertical section through part of the side wall of the tubular member showing a somewhat different form of retaining recess for the bottom disc;

Fig. 5 is a vertical section of part of a further modified construction of the tubular member;

Fig. 6 is a vertical section of part of a still further modified construction of the holder or tubular member;

Fig. 7 is a perspective view of an open ended tubular member differing from that shown in Fig. 1 in that it has doubly flared sides;

Fig. 8 is a perspective view of a still further modification of the tubular member which is flared continuously from one end to the other; and

Fig. 9 is a perspective view of still another form of the open-ended tubular section.

As shown in Fig. 1, the receptacle is made of a straight sided tubular member or ring 10 and a flat circular bottom disc 12. The ring 10 is provided with an internal groove or recess 14 which may be advantageously rolled into the ring while it is held in a die or form. As shown, the ring comprises a wall 16 made of sulphite tag stock faced with long fiber asbestos paper 16a and an outer layer of smooth paper 18, which may be colored and printed or otherwise decorated to impart a pleasing appearance or to display advertising.

The bottom disc 12 may be made of asbestos mill board and is intended to have suitable advertising matter or a decoration printed or otherwise impressed on both sides. In place of mill board, I may use, and have shown in Figs. 2 and 3, a laminated sheet material, which may, for example, comprise long fiber asbestos paper 12a laminated on both sides of a relatively stiff and water impervious paper layer 12b, such as chipboard or sulphite tag stock. Other mate-

rials having fire resistant properties may be used provided they also combine therewith sufficient stiffness or strength to serve as a support for the uses intended and, at the same time, are capable of being flexed sufficiently to enable them to be sprung into place and removed from the holder as desired.

In the process of manufacture, the asbestos ring or holder may be formed in various ways, one advantageous method being to form a tubular member of the length conforming to the width of the asbestos sheet, laminated or otherwise, as it comes from the manufacturer. This tube is then severed into rings of the desired length and thereafter a layer of paper is applied to the outer wall of the ring and crimped over the ends, as shown at 20. The beading or rolling of the inner wall of the ring to provide the bottom supporting recess or ledge may be effected either after the ring has been severed from the original tube section or while the tube section is intact and before severing of the rings.

The disc retaining recess 14 may be formed in various other ways. Examples are shown in Figs. 4, 5 and 6. In Fig. 4 the ring 10 is shown as made up of a wall 16 of sulphite tag stock faced on its inner side with long fiber asbestos paper 16a and an outer layer of paper 18 crimped over the ends of the ring as at 20. However, in this form the bottom disc retaining groove is shown as produced by forming two parallel annular beads 15 on the inner periphery of the ring, these beads being so spaced as to define therebetween a groove 14b adapted to receive the peripheral edges of the disc and retain the disc in spaced position with respect to the ends of the ring. As shown, the bead is produced by running a suitable beading instrument around the outside of the ring after the paper layer 18 has been applied and while holding the ring on a mandrel or other suitable means designed to prevent inward displacement of the walls except along the lines desired. The use of a single bead defining a ledge upon which the bottom disc will rest in either position of the holder is also within the scope of my invention.

In Fig. 5 still another form of wall construction is shown. In this modification the ring 10 is made up of a sulphite tag board ring section 22, an outer smooth paper layer 18 and a pair of shorter asbestos rings 16c associated with the section 22 respectively adjacent its ends and leaving between them a recess or shoulder 14c. The rings 16c are secured to the section 22 by a suitable adhesive and the edges 20 of the outer paper layer 18 are curled over the ends of the section 22 and the rings 16c and secured to the rings 16c by an adhesive.

In Fig. 6 the open-ended tubular section or holder 10 is shown as formed of an inner ring section 22 which may be, for example, made of sulphite tag board and an outside smooth paper layer 18 which is curled over the ends of the section 22 and extends down the inner wall of 22 from both ends but not quite meeting, thereby defining between them a recess or groove 14d adapted to receive the edges of the circular bottom disc 12 and hold this disc against accidental displacement. When the ring is to be used in forming an ash tray, the paper layer 18 is selected from those having fire resistance.

In Fig. 7 the open-ended tubular section 10 is shown as flared outwardly toward both ends from a middle point adjacent the circular groove 14. The opposite edges of the ring are also shown

as cut away at 26 to provide cigarette rests. Otherwise the construction is the same as that of Fig. 1 and is subject to modification according to the constructions of any of Figs. 3, 4, 5 and 6.

Fig. 8 shows still another modification differing from the preceding in being flared outwardly from the one end, at 28, toward the other end, at 30.

Fig. 9 shows still another modification in which the open-ended tubular member 10 is made rectangular in cross section but is otherwise of the same general construction as shown in the preceding figures.

Where the term "ash tray" is used in the claims, it is to be understood as including other shallow receptacles adapted for similar uses, such as coasters and the like.

It is to be understood that the forms of the invention shown in the drawing are intended to be illustrative and are not to be construed as limiting the scope of the invention except as set forth in the appended claims.

I claim:

1. An ash tray comprising a one-piece open-ended shallow tubular member and a separable one-piece bottom member cooperating to produce a reversible tray, said tubular member being provided intermediate its top and bottom with an inner peripheral groove equally spaced from the

ends of said tubular member and dividing the member into halves of similar shape and size, said groove operating to support and hold said bottom member in spaced relation to a supporting surface, and said bottom member being brought into pressure engagement with said supporting means and flexed into and out of pressure engagement throughout the periphery of the groove with said supporting means without dismantling said tubular member.

2. A reversible ash tray comprising a one-piece open-ended shallow tubular member defining the side walls and a one-piece bottom disk, said tubular member including an inner shallow tubular section of relatively stiff self-supporting paper stock and an outer tubular section of relatively flexible sheet material, said outer section having its opposite ends crimped over the ends of the inner tubular section and extending along the inner peripheral surface thereof toward one another, and thereby defining a peripheral recess therebetween equally spaced from the ends of said tubular member, said recess dividing said tubular member into halves of similar shape and size and operating to support and hold said bottom disk in spaced relation to its supporting surface in either of the two upright positions that may be assumed by said tubular member.
